The ornamental design for an input pen for electronic device, as shown and described.

DESCRIPTION

FIG. 1 is a front perspective view of an input pen for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the portion A encircled in FIG. 2.

The broken lines illustrating portions of the input pen for electronic device are for environmental purposes only and form no part of the claimed design.

The dot-dash broken lines encircling portions of the claimed design that are illustrated in enlargements form no part of the claimed design.

The dot-dash lines in the figures represent an unclaimed boundary line and form no part of the claimed design.
